ELECTRIC SCISSORS

Alan F. Eckel, Chicago, Ill., assignor to Sears, Roebuck and Company, Chicago, Ill., a corporation of New York

Continuation of design applications Ser. No. 11,504 and Ser. No. 11,506, Apr. 18, 1968. This application Dec. 13, 1968, Ser. No. 18,105

Term of patent 14 years

Int. Cl. D8—02

U.S. Cl. D8—61

Fig. 10

FIG. 1 is a perspective view of an electric scissors showing my new design;

FIG. 2 is a top plan view thereof;

FIG. 3 is a side elevation thereof;

FIG. 4 is a rear elevation thereof;

FIG. 5 is a bottom plan view thereof;

FIG. 6 is a perspective view of an electric scissors showing a modified form of the design shown in FIGS. 1-5 and differing primarily therefrom in the shape of the bottom wall and the bulb-blade recess at the forward end of the device.

FIG. 7 is a top plan view of the electric scissors shown in FIG. 6;

FIG. 8 is a side elevation of the electric scissors shown in FIG. 6;

FIG. 9 is a rear elevation of the electric scissors shown in FIG. 6; and

FIG. 10 is a bottom plan view of the electric scissors shown in FIG. 6.

This is a continuation of design applications Ser. Nos. D. 11,504 and D. 11,506, both filed Apr. 18, 1968, and both now abandoned.

I claim:

The ornamental design for an electric scissors, as shown and described.
